UNITED STATES PATENT OFFICE.

ALEXANDER B. HILL, OF HOBOKEN, NEW JERSEY.

GAME APPARATUS.

1,025,465.

Specification of Letters Patent.

Patented May 7, 1912.

Application filed August 22, 1911. Serial No. 645,417.

To all whom it may concern:

Be it known that I, ALEXANDER B. HILL, a citizen of the United States, residing at the city of Hoboken, Hudson county, in the 5 State of New Jersey, have invented certain new and useful Improvements in Game Apparatus, of which the following is a full, clear, and exact specification.

My invention relates to improvements in 10 game apparatus, and the same has for its object more particularly to provide an apparatus comprising essentially a support having two series of receptacles arranged thereon and one of said series disposed in a 15 horizontal plane above the plane of the other of said series, and a projectile loosely disposed upon said receptacle adapted to be projected therefrom and caused to enter one of said receptacles.

20 Further said invention has for its object to provide a simple, inexpensive and convenient portable apparatus which may be placed upon a table or other suitable support when in use and when not in use be 25 dismounted and assembled within a small compass for packing and storing.

To the attainment of the aforesaid objects and ends my invention consists of the novel 30 details of construction and in the combination, connection and arrangement of parts hereinafter more fully described and then pointed out in the claims.

In the accompanying drawings forming 35 part of this specification wherein like numerals of reference indicate like parts, Figure 1 is a plan or top view showing one form of game apparatus constructed according to and embodying my said invention; Fig. 2 is a section taken on the line 2—2 of 40 Fig. 1; Fig. 3 is an enlarged detail central vertical section of the projectile, and Fig. 4 is a detailed perspective view showing the construction of one of the supporting members.

45 In said drawings 10 designates the apparatus as a whole comprising a circular plate or table 11, having its upper surface and edge covered with a covering 12 which is preferably made of felt or other somewhat elastic material, and secured thereto by glue or other convenient agency.

50 13 denotes a short tube section or nozzle arranged centrally upon the plate or table 11, and projecting partly above and partly 55 below the same. Adjacent to its upper edge said tube section or nozzle 13 is provided

with a laterally projecting flange 14 which is adapted to rest upon the upper surface of the plate or table 11 in order to support said tube section or nozzle 13 properly positioned 60 upon said plate or table.

15 denotes a series of hemispherical receptacles arranged upon the plate or table 11 and surrounding said tube or nozzle 13. Said receptacles 15 are provided with numerals or other indicating devices to designate the values of said receptacles, such as 10, 20, 30, 40, and 50. The value of said receptacles increases in value as the said receptacles recede from the nozzle 13 and 70 approach the outer edge of said plate or table 11.

16 denote supports or uprights which are detachably secured to the edge of the plate or table 11 in order to support the same in 75 an elevated position. Each of said supports is formed of a rectangular post having a transverse recess 17 in one of its sides, of such size as to receive the edge of the plate or table 11 and hold the same in frictional 80 engagement therein. At the lower end of each of said supports is secured a bearing 18 within which is mounted a roller 19.

Upon the upper end of each support or post 16 is secured a hemispherical receptacle 85 20 which is considerably larger in diameter than said receptacles 15 and is arranged in a horizontal plane considerably above the plane of said receptacles 15. The said larger receptacles 20 are few in number as 90 compared with the smaller receptacles 15 and are therefore accorded a higher relative value, in the present instance 100, which is materially greater than the highest value assigned to any receptacle secured to the 95 plate or table 11.

The receptacles 15 and 20 may be secured to their respective supports by any suitable means. In the present construction the same are shown as secured in position by 100 means of nails 21 provided with flat heads and passing centrally through the bases of said receptacles and into the supports therefor.

22 denotes a flexible rubber tube having one 105 end secured to the portion of the nozzle 13 projecting below the plate or table 11. To the other end of such tube 22 is secured a bulb 23, or other suitable compression device.

24 denotes a projectile which is preferably made of light material such as cellu-

2
loid and hollow and open at its base in order that the same may be readily fitted over the upwardly projecting end of the nozzle 13. The said projectile is made of such shape and dimension as to receive the compressed air blast delivered by said nozzle when the bulb 23 is compressed in order to cause said projectile to be thrown upwardly into the air a sufficient distance to insure its falling into the outermost of the receptacles 15 or the receptacle 20 mounted on the upper ends of the support 16.

It will be quite obvious that instead of the bulb 23, any suitable compression device may be employed and that the same result may be obtained without the aid of a compression device by applying a suitable mouth piece to the outer end of the flexible tube 22 and blowing into the same.

20 Having thus described my invention what I claim and desire to secure by Letters Patent is:

1. A game apparatus comprising a plate, means for supporting said plate arranged along the edges thereof, a nozzle projecting upwardly from said plate, receptacles arranged upon said plate and surrounding said nozzle, a hollow projectile adapted to be fitted upon said nozzle, a second series of receptacles mounted upon the supporting means for said plate, and arranged bodily in a horizontal plane above the plane of said first mentioned receptacles, and means connected to said nozzle for projecting said projectile, substantially as specified.

2. A game apparatus comprising a plate, means for supporting said plate in elevated position arranged along the edges thereof and detachably engaging said edges, a nozzle extending through said plate, a series of receptacles arranged upon said plate and substantially covering the same, a second series of larger receptacles arranged upon the upper ends of the supporting means for said plate and arranged in a horizontal plane above the plane of said first mentioned receptacles, a hollow projectile adapted to be fitted upon said nozzle, a flexible tube connected to the lower end of said nozzle, and a compression device connected

to the other end of said tube for projecting said projectile, substantially as specified.

3. A game apparatus comprising a plate, a plurality of detachable supports frictionally engaging the edge of said plate intermediate their ends, a nozzle extending centrally through said plate, separate receptacles secured upon said plate and surrounding said nozzle; said receptacles having values indicated thereon increasing as the same recede from said nozzle, a second series of receptacles mounted upon the ends of said detachable supports in a plane above said plate and the supports thereon, said second series of receptacles bearing values greater than those of any of the receptacles arranged upon said plate, a hollow projectile adapted to be fitted upon said nozzle, and a compression device connected to said nozzle for projecting said projectile, substantially as specified.

4. A game apparatus comprising a circular plate having an elastic covering thereon extending over the edge thereof, a plurality of supports provided with transverse recesses adapted to engage the edge of said plate intermediate the ends of said supports whereby to support said plate in elevated position, a nozzle centrally arranged upon said plate and extending partly above and partly below the same, a series of separated receptacles secured upon said plate and surrounding said nozzle, a second series of receptacles mounted upon the ends of said detachable supports and arranged bodily in a plane above the plane of said first mentioned receptacles, a projectile provided with an opening in its base adapted to be fitted upon said nozzle, a tube connected at one end to said nozzle, and a bulb connected to the other end of said tube for projecting said projectile, substantially as specified.

Signed at the city of New York, in the county and State of New York, this 7th day of August, nineteen hundred and eleven.

ALEXANDER B. HILL.
